UNITED STATES PATENT OFFICE.

MARIE ELIZABETH JAMME, OF SUMMIT, NEW JERSEY.

PRESCRIPTION-CORSET.

1,088,993.

Specification of Letters Patent.

Patented Mar. 3, 1914.

Application filed January 30, 1913. Serial No. 745,072.

To all whom it may concern:

Be it known that I, MARIE E. JAMME, a citizen of the United States, residing at Summit, Union county, New Jersey, have invented certain new and useful Improvements in Prescription-Corsets, of which the following is a full, clear, and exact description.

My invention relates to prescription corsets, and has for its object to produce a corset which will aid in curing what is known as enteroptosis, a trouble which is due to want of tone in the abdominal walls, and similar abdominal ills.

The following is a description of an embodiment of my invention, reference being had to the accompanying drawings, in which—

Figure 1 represents a perspective view of the front of a corset embodying my invention. Fig. 2 shows the same on a wearer. Fig. 3 is a side elevation of one of the steels of the first series. Fig. 4 is a similar view of a steel of the second series. Fig. 5 is a side elevation and front view of a steel of the third series.

Referring more particularly to the drawings, 1 is a corset body having comparatively straight sides 2—2'. 3'—3²—3³—3⁴ are four strong steels, made preferably of hard copper, because of its ability to keep its shape. Between the two central steels 3²—3³ are lacings 4—4', so that the corset can be given a V-shaped opening in front and adjusted somewhat to the size of the wearer. The right hand steels, 3³—3⁴, have the ordinary loops 5 and studs 6 for holding the corset about the wearer. The steels 3'—3²—3³—3⁴ all have an abrupt outward bend near their lower ends, most prominent in the first series (Fig. 3), followed by a downward bend also shown in Fig. 3, so as to form an inward projection above the lower ends of the steels whose apex 7 exerts pressure on the region below the umbilical region, which former region is known as the hypogastric region of the abdomen. The steel between this apex and its upper end is substantially straight. I term the inward projection formed in the steels a "hypogastric projection".

I find it desirable to have at least three series or sets of steels, about eleven inches long and three-eighths of an inch wide, one set in which the hypogastric projection is quite pronounced as shown in Fig. 3, a sec-

ond set in which it is somewhat less as in Fig. 4, and a third in which the projection is somewhat lower down and still less abrupt as shown in Fig. 5.

In an early stage of enteroptosis a corset with the steels of Fig. 3 is prescribed and worn. As the patient improves, a corset with the steels of Fig. 4 is substituted, and later a corset with the steels of Fig. 5, after which, when the patient recovers, the ordinary commercial corset can be used.

The hypogastric projection supports the walls and muscles of the abdomen and the viscera therein so as to not only enable the parts to build up and return to normal condition, but to render the patient much more comfortable while the healing process is going on.

In order not to cause too much pressure over the diaphragm and insure ample thorax room, the front of the corset should be laced V-shaped, as shown. The desired looseness at the upper portion can be best secured by using two sets of lacings 4—4'. The lower ends of the steels should be covered with chamois 8 or the like, to protect the fabric of the corset against wear. The lower part of the corset below the steels is secured by hooks 9.

As will be evident, my invention permits of various modifications without departing from the spirit thereof or the scope of the appended claims.

What I claim is:

1. A corset consisting of a corset body and a plurality of steels in the front thereof, said corset having an inwardly extending hypogastric projection above the lower ends of the steels, and means for holding the said parts about the wearer.

2. In a corset, the combination of a corset body, a plurality of steels in the front thereof, said steels having inwardly extending hypogastric projections above the lower ends of the steels, and hooks and studs on two adjacent steels.

3. In a corset, the combination of a corset body, a plurality of steels in the front thereof, said steels having inwardly extending hypogastric projections above the lower ends of the steels, and a lacing between two of said steels.

4. In a corset, the combination of a corset body, a pair of steels in the front thereof, said steels having inwardly extending hypogastric projections above the lower

ends of the steels, a lacing between said steels, and additional means for holding the parts about the wearer.

5. In a corset, the combination of a cor-
set body, two pairs of steels in the front
thereof, said steels having inwardly extend-
ing hypogastric projections above the lower

ends of the steels, a lacing between said pairs, and studs and loops on the two mem-
bers of one pair respectively.

MARIE ELIZABETH JAMME.
